CONTROL DEVICE FOR WINDING MACHINES

Edward J. Heizer, West Caldwell, and Meredith R. Stuart, Belleville, N. J., assignors to Specialties Development Corporation, Belleville, N. J., a corporation of New Jersey

Application December 19, 1946, Serial No. 717,188

11 Claims. (Cl. 242—18)

1

The present invention relates to machines for winding yarn, thread or other filaments, and more particularly relates to improvements in devices for controlling the density and size of the packages wound by such machines.

The present invention is adapted to be practiced in connection with winding machines in which a thread is caused to reciprocate while feeding onto a package through means carried by a support known as a back, the package being wound on a rotatable package support, the back and the support being relatively movable and being adapted to be urged into separated position by the action of gravity or other suitable means. The thread guide is maintained either at a predetermined light pressure in contact with, or barely out of contact with, the surface of the package being wound, whereby the density and size of the package may be accurately controlled. To accomplish this, the package support and the back may be locked against relative separating movements by suitable escapement means which are adapted to be released intermittently as the package grows in size under the control of means contacting the package such as a feeler roll. This feeler roll is adapted to be rotated upon frictional engagement with the rotating package being wound to effect actuation of means controlling the release of the locking means.

Accordingly, an object of the present invention is to provide improved escapement means for a winding machine of the foregoing character.

Another object is to provide improved locking means for the escapement means which are adjustable to determine the friction required between the feeler roll and the package to effect release of the locking means.

Another object is to provide means for adjusting the density of the package by means of the feeler roll.

Another object is to provide an escapement having means adapted to take up the back-lash of the gear train of the escapement when the back is pushed against the package.

Another object is to provide a spring for assisting separation of the back and package under the influence of gravity.

A further object is to provide improvements of the foregoing character which are positive in operation, rugged in construction, are not likely to get out of order, and do not require supervision or repair.

Other and further objects of the invention will be obvious upon an understanding of the illustrative embodiment about to be described, or will

2

be indicated in the appended claims, and various advantages not referred to herein will occur to one skilled in the art upon employment of the invention in practice.

5 A preferred embodiment of the invention has been chosen for purposes of illustration and description and is shown in the accompanying drawings, forming a part of the specification, wherein:

10 Figure 1 is a fragmentary perspective view of the back and package support portion of a winding machine embodying the present invention with the back retarding means broken away.

15 Figure 2 is a fragmentary side elevational view, illustrating in detail the means for retarding separation of the back and package with the cover removed therefrom.

20 Figure 3 is a front elevational view of the retarding means shown in Figure 2 illustrating details thereof.

Figure 4 is an enlarged fragmentary perspective view of latch control means.

25 In practicing the present invention, any desired winding machine of commercial construction may be employed insofar as the elements for supporting and rotating the winding spindle and for imparting traversing movement to the thread guide are concerned. Accordingly, in Figure 1 there is shown only one of the upright side frames 10 of such a winding machine. A horizontal spindle 11 is supported in this frame by suitable journal boxes and is arranged to be rotated at high speed. The spindle has a flange at its inner end and a removable collar at its outer end between which is clamped a cap or bobbin on which the thread package 14 is to be wound.

30 A back carrying the thread guide is supported to rock freely about the axis of a shaft 15 projecting outwardly from the side frame 10, whereby the package supporting spindle 11 and the back are arranged for relative separating movement. The back includes an upwardly extending arm 16 carrying a transversely extending frame 17 provided with a bearing for a slide 18 from which extends an upright arm 19 carrying a thread guide 20. The slide 18 is reciprocated at high speed by a cam mechanism (not shown) to traverse the thread guide 20 back and forth in a longitudinal path parallel to the surface of the thread package 14.

35 In the upper portion of the frame 17, an elongated yoke 21 is secured having forwardly extending arms at each end between which is journaled a long feeler roll 22. This roll is pivoted

for rotation or pivotal movement about its longitudinal axis and is adapted to engage the rotat-
ing package 14 being wound as it grows in size,
whereby the roll is turned about its pivot. Such
turning of the roll is utilized to control the sep-
aration of the back and package support in re-
sponse to the growth of the package as will ap-
pear hereinafter.

Separation of back and package normally is
prevented by retarding means herein illustrated
(Figures 2 and 3) as an escapement mechanism
25 which is secured to the side frame 10 by a
bracket 26.

The escapement mechanism comprises a
spaced apart pair of side frames 27 and 28 hav-
ing a rotatable hollow shaft 29 journaled therein
having its axis in alignment with the axis of the
shaft 15. The inner end of the shaft extends
beyond the side frame 28 and has an arm 30
secured thereto which has a slot 31 at its free end
for receiving a stud 32 on an extension 34 of the
arm 16 (Figures 1 and 2), whereby the back and
escapement mechanism are operatively con-
nected.

A gear 35 is mounted for rotation on the shaft
29 between the side frames 27 and 28 and is con-
nected for rotation with the shaft 29 by clutch
means comprising a member 36 having a face
frictionally engaging one side of the gear 35 and a
second member 37 having a face frictionally
engaging the other side of the gear 35. In this
manner the back can be moved towards and away
from the package by applying a force overcom-
ing the clutch friction without imparting rota-
tive movement to the gear 35 through the ex-
tension 34, the arm 30 and the shaft 29.

The clutch members 36 and 37 are connected
for rotation with the shaft 29 and are connected
for rotation with each other by an extension 39
on the member 36 having a slot 40 and an ex-
tension 41 on the member 37 having a lateral
projection 42 extending into the slot 40. The
clutch members are urged to rotate the shaft 29
in a direction to assist moving the back away
from the package through the arm 30 and ex-
tension 34 by means of a spring 44 coiled about
the shaft 29 and having one end secured to the
side frame 28 and having its other end secured
to the clutch member 37.

Rotation of the gear 35 normally is prevented
by an escapement pawl 45 engaging a star wheel
46 which is connected to the gear 35 by a train
of gears 48, 49, 50, 51 and 52 rotatably mounted
on the side frames of the escapement mecha-
nism 25. The pawl 45 is mounted for oscillating
movement to permit the same to move out of and
into engagement with the star wheel 46. This
is accomplished by a rod 54 extending through
the hollow shaft 29 having the pawl 45 secured
thereto at one end thereof and having a latch
segment 55 secured thereto at the other end
thereof.

A device is provided to take up the back-lash
of the gear train when the back is pushed against
the package which back-lash allows the back to
fall away from the package by the amount of
back-lash. This device comprises a rotatable
rubber covered wheel 56 and a spring-like arm
57 having the wheel 56 mounted on one end
thereof and having its other end secured to the
cover of the retarding means (Figure 3). When
the wheel 56 is manually pushed and turned
counterclockwise it engages the star wheel and
turns it, which rotates the gear train sufficiently

to move the back the amount that it had fallen
away.

The segment 55 has a series of detents adapted
to be engaged by a latch element 60 (Figures 1,
2 and 4) on one end of an arm 61 pivoted at its
other end on a bracket 62 secured to the exten-
sion 34 of the back. The latch element shown
herein is formed of spring steel to absorb shock
upon engagement of the detents and is mounted
to jump out of engagement to allow the back to
be moved manually. This is accomplished by
forming a pair of recesses 64 on the underside of
the arm 61 which are spaced apart by an opening
65. The latch element has upwardly facing
edge portions 66 seated in the recesses and has a
portion 67 of reduced width extending through
the opening 65. The portion 67 has one end of
a spring 69, under tension, secured thereto and
the other end of the spring is secured to a yoke
70 mounted on the arm 61.

The latch element is adapted to be moved out
of the detents of the segment 55 upon lifting the
arm 61. The latter is accomplished by linkage
means mechanically connecting the feeler roll
22 and the arm 61. As shown herein, such link-
age means may comprise a link 71 such as a
wire-like rod having one end secured to the arm
61 and a chain 72 or the like having one end con-
nected to the other end of the link 71 and hav-
ing its other end connected to the feeler roll in
a manner to exert a pull on the link upon turn-
ing of the feeler roll, whereby the feeler roll
causes the latch element to be lifted out of the
detents of the segment 55.

In order to control the density of the package
being wound, the friction between the package
and the feeler roll necessary to effect turning of
the latter by the former is varied by increasing
or decreasing the force on the chain opposing
turning of the roll. This is accomplished by
mounting removable weights 74 on a pin 75 se-
cured to the arm 61. By increasing the number
of weights the force opposing the rotation of the
roll is increased and likewise the friction neces-
sary to effect rotation of the roll by the package
is increased, whereby the roll exerts greater pres-
sure on the package to produce a more densely
wound package. The opposite effect is accom-
plished by reducing the number of weights.

In operation, when the thread package is be-
ing wound, the back is moved towards the spindle
11 by hand with sufficient force to overcome the
friction between the clutch members 36 and 37
to position the feeler roll 22 on the surface of
the package 14 or the cop on which the package is
to be wound. As the package grows in size the
friction contact between the feeler roll and pack-
age gradually increases until the package effects
turning of the feeler roll. The chain 72 is then
wound on the feeler roll and exerts a pull which
is effective through the link 71 to raise the latch
arm 61 to thereby cause the latch element 60 to
release the latch segment 55.

When the latch segment is released, the rod
54 carrying the escapement pawl 45 is free to
oscillate, thus releasing the pawl to enable the
star wheel 46 to rotate step by step. The back is
then free to move away from the spindle under
the influence of gravity and the spring 44, but the
back moves away very slowly due to the train of
gears 48, 49, 50, 51 and 52 between the star
wheel and the back.

As the back and package separate, the feeler
roll is moved out of contact with the surface of
the thread package or only lightly contacts the

package to permit the roll to return to its initial position under the influence of the weight of the latch arm 61 connected thereto by the link 71 and chain 72. The latch element then enters one of the detents of the latch segment 65 to lock the rod 54 carrying the pawl, whereby the pawl prevents further movement of the star wheel. When the package again grows in size these operations are repeated.

From the foregoing description it will be seen that the present invention provides an improved arrangement for periodically and intermittently locking the back and releasing the back for separation with respect to the package. The separation of the back and package is assisted by the spring which together with the influence of gravity provides a substantially uniform separating force throughout the entire range of movement of the back. The take-up enables the feeler roll to be placed in contact with the package at the commencement of the winding operation, whereby the package need not build up prior to being engaged by the roll. This enables the feeler roll to control the density of the package throughout the entire winding thereof. The variable weights for increasing or decreasing the frictional contact between the feeler roll and the package enable the density of the package to be accurately controlled.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

The general arrangement of a latch, package contacting means and a mechanical connection between the latch and the package contacting means, illustrated and described herein, constitutes the subject matter of copending application Serial Number 704,400, filed October 19, 1946, now Patent No. 2,486,031, dated October 25, 1949.

We claim:

1. In a winding machine comprising a rotatable package support and thread guide supporting means, the supporting means and the package support being relatively movable into separated position under the influence of gravity; the combination of means for contacting the package adapted to be operated thereby as the package grows in size, means for retarding separation of the supporting means and the package support including locking means controlled by said contacting means, and a spring member for assisting the force of gravity to effect separation of the supporting means and the package support.

2. In a winding machine comprising a rotatable package support and thread guide supporting means, the supporting means being movable into separated position with respect to the package support under the influence of gravity; the combination of means for contacting the package adapted to be operated thereby as the package grows in size, escapement means for retarding separation of the supporting means and the package support including a train of gears and locking means controlled by said contacting means, clutch means connecting said train of gears and the supporting means, and a spring member for urging said clutch means in a direction to assist the force of gravity to effect separation of the supporting means and the package support upon release of said locking means.

3. In a winding machine comprising a ro-

tatable package support and thread guide supporting means, the supporting means and the package support being relatively movable into separated position under the influence of gravity; the combination of an escapement device including a train of gears for retarding separation of the supporting means and the package support, means connecting said device and the supporting means, and a manually operable device for rotating one of the gears of said train of gears to move the supporting means towards the package support.

10. In a winding machine comprising a rotatable package support and thread guide supporting

means, the supporting means and the package support being relatively movable into separated position under the influence of gravity; the combination of an escapement device including a train of gears for retarding separation of the supporting means and the package support, a friction clutch connecting said device and the supporting means to permit the supporting means to be moved manually towards the package support, and a manually operable device for rotating one of the gears of said train of gears to move the supporting means towards the package support through said train of gears and said clutch.

15. In a winding machine comprising a rotatable package support and thread guide supporting means, the supporting means and the package support being relatively movable into separated position under the influence of gravity; the combination of an escapement device including a train of gears, a star wheel and a pawl for retarding separation of the supporting means and the package support, means connecting said device and the supporting means, and a manually operable device for rotating said star wheel to move the supporting means towards the package support through said train of gears and said connecting means.

20. In a winding machine comprising a rotatable package support and thread guide supporting means, the supporting means and the package support being relatively movable into separated position under the influence of gravity; the combination of an escapement device including latch means and a train of gears for retarding separation of the supporting means and the package support, clutch means connecting said device and supporting means, a spring for urging said clutch means in a direction to assist the force of gravity in effecting separation of the package support and the supporting means upon release 25 of said latch means, and a manually operable device for rotating one of the gears of said train of gears to move the supporting means towards the package support.

25. In a winding machine comprising a rotatable package support and thread guide supporting means, the supporting means and the package support being relatively movable into separated positions; the combination of means for locking the supporting means and the package support against relative separating movement including a latch, means for contacting the package and operable thereby as the package grows in size, linkage means mechanically connecting said contacting means and said latch constructed and arranged whereby operation of said contacting means effects raising of said latch, and weight means carried by said latch.

30. In a winding machine comprising a rotatable package support and thread guide supporting means, the supporting means and the pack-

age support being relatively movable into separated position; the combination of means for locking the supporting means and the package support against relative separating movement including a latch, means for contacting the package and operable thereby as the package grows in size, linkage means mechanically connecting said contacting means and said latch constructed and arranged whereby operation of said contacting means effects raising of said latch, and weight means removably attached to said latch.

9. In a winding machine comprising a rotatable package support and thread guide supporting means, the supporting means and the package support being relatively movable into separated position; the combination of means for locking the supporting means and the package support against relative separating movement including a latch arm, a feeler roll for contacting the package and operable thereby as the package grows in size, linkage means mechanically connecting said feeler roll and said latch arm constructed and arranged whereby operation of said contacting means effects raising of said latch arm, and weight means removably mounted on said latch arm.

10. In a winding machine comprising a rotatable package support and thread guide supporting means, the supporting means and the package support being relatively movable into separated position under the influence of gravity; the combination of an escapement device including a train of gears for retarding separation of the supporting means and the package support, a cover for said device having a slot therein; means

5 connecting said device and the supporting means, and a wheel yieldingly mounted on said cover and manually accessible through said slot for engaging and rotating one of the gears of said train of gears to move the supporting means towards the package support.

11. In a winding machine comprising a rotatable package support and thread guide supporting means, the supporting means and the package support being relatively movable into separated position under the influence of gravity; the combination of an escapement device including a train of gears, a star wheel, and a pawl for retarding separation of the supporting means and the package support, a cover for said device having a slot therein, a friction clutch connecting said device and the supporting means to permit the supporting means to be moved manually towards the package support, and a wheel yieldingly mounted on the inside of said cover and manually accessible through said slot for engaging and rotating said star wheel to move the supporting means towards the package support through said train of gears and said clutch.
